US0D1074300S

(12) **United States Design Patent** (10) **Patent No.:** **US D1,074,300 S**
(45) **Date of Patent:** **** May 13, 2025**

(54) **DETACHABLE FLIP-STRAW LID**

(71) Applicant: **Hydrojug, Inc.**, Ogden, UT (US)

(72) Inventors: **Hayden Wadsworth**, Ogden, UT (US); **Ethan Powell**, Salt Lake City, UT (US); **Ryan Holmes**, West Haven, UT (US); **Chen Huawen**, Yongkang (CN); **Chen Wiexin**, Yongkang (CN); **Li Yuejian**, Yongkang (CN); **Qiu Hui**, Hangzhou (CN); **Wang Wei**, Hangzhou (CN)

(73) Assignee: **Hydrojug, Inc.**, Ogden, UT (US)

(**) Term: **15 Years**

(21) Appl. No.: **29/961,782**

(22) Filed: **Sep. 7, 2024**

(57) **CLAIM**

The ornamental design for a detachable flip-straw lid as shown and described.

DESCRIPTION

FIG. 1 is a first perspective view of a detachable flip-straw lid design, showing our new design;

FIG. 2 is a first side view thereof;

FIG. 3 is a second side view thereof;

FIG. 4 is a third side view thereof;

FIG. 5 is a fourth side thereof;

FIG. 6 is a top view thereof;

FIG. 7 is a bottom view thereof;

FIG. 8 is a perspective view thereof in a first alternate position of use with the handle raised;

FIG. 9 is a perspective view thereof in a second alternate position of use with the handle down and with the straw raised; and,

FIG. 10 is an exploded perspective view thereof in a third alternate position of use with the straw detached from the lid.

The dashed lines depict portions of the detachable flip-straw lid that form no part of the claimed design.
